UNITED STATES PATENT OFFICE.

JOSEF LEITER, OF VIENNA, AUSTRIA.

IMPROVEMENT IN HYPODERMIC SYRINGES.

Specification forming part of Letters Patent No. 159,192, dated January 26, 1875; application filed January 12, 1875.

To all whom it may concern:

Be it known that I, JOSEF LEITER, of Vienna, Austria, have invented a certain new and Improved Hypodermic Syringe, of which the following is a specification:

This invention is illustrated in the accompanying drawing, in which—

Figure 1 represents a longitudinal section. Fig. 2 is a side view of the same. Fig. 3 is a cross-section in the line $x x$, Fig. 1.

Similar letters indicate corresponding parts.

This invention consists in an apparatus for a painless subcutaneous injection in the cellular tissue of the human skin, and is composed of a cylindrical tube, inside of which a small sliding syringe is arranged, with a mouth-piece or spout forming a sharp-pointed needle or lancet.

The piston of said syringe is operated by a sliding head, upon which acts a spring, which, if the head is drawn back and then released, forces said head with rapidity against the piston of the syringe, and, at the same time, the syringe is pushed forward, and the lancet-shaped spout enters the cellular tissue of the skin, where the contents are injected.

This operation is performed with great rapidity, in preference of the slow, painful, and uncertain proceedings as heretofore done by the hand of the physician.

In the drawing, the letter a designates a cylindrical tube, inside of which are situated a spiral spring, b , and a slide or head, c . A second tube, d , is screwed to the tube a , and over this tube is fitted a sleeve, the outer end of which forms a cone, r , to allow the lancet-shaped spout g of the syringe e to pass through, and to enter that part of the human body against which the apparatus is held in an inclined direction, the inclination being determined by the tapering end of the sleeve f .

The tube d , which contains the syringe e , is provided with a shoulder, l , to stop the forward motion of the syringe. The rod o of the piston p is provided with a regulating-screw, m .

The spring b is compressed by pulling the slide c back, which is done by a handle or trigger, h , projecting through a slot, i , in the tube a . On the end of the slot i recesses k are formed, and by turning the trigger h into

one of these recesses the sliding head c is held in position.

In operating my apparatus, the syringe is first filled with the liquid to be injected; then the sliding head c is drawn back and locked by the trigger h and one of the recesses k , and the apparatus is placed in the desired position on the human body, and the slide c is released by touching the trigger h , so as to force the syringe forward to the end of the tube d , and, since the syringe is stopped in its forward movement by the shoulder l in said tube, the piston is pressed into the barrel of the syringe, and the liquid is ejected.

To regulate the quantity of liquid to be injected, the syringe may be partially filled, or, if several injections are to be made out of one filling, the piston-rod, which may be divided in proportional parts, is set to a certain division by its regulating-screw to stop the action of the syringe at the required spot.

The tapering end, r , of the sleeve f forms the base of the apparatus during its operation. Said sleeve can also be adjusted to control the depth to which the lancet g enters the skin.

The tube d is provided with a scale, so as to be able to regulate the position of the sleeve f .

The operation of my apparatus, being exceedingly rapid and automatic, is entirely free from pain. It can be regulated with exactness, and it is free from all danger.

What I claim as new, and desire to secure by Letters Patent, is—

1. The combination of a regulating-sleeve, f , with a syringe, e , provided with a lancet-shaped spout, g , substantially as described.
2. The regulating-screw m , in combination with the syringe e , tube d , and regulating-sleeve f , substantially as set forth.
3. The combination of a head or hammer, c , and trigger h with a syringe, e , and guide-tube d , substantially as described.

In testimony that I claim the foregoing I have hereunto set my hand this 2d day of December, 1874.

JOSEF LEITER.
